(57) **CLAIM**

The ornamental design for a designer crib sheet set, as shown and described.

DESCRIPTION

FIG. 1 is a top plan view of the designer crib sheet set of the present invention;

FIG. 2 is a top, front and left side perspective view of the designer crib sheet set of FIG. 1;

FIG. 3 is a top, bottom and left side prospective view of the designer crib sheet set of FIG. 1; and,

FIG. 4 is a top, front and left side perspective view of an alternate embodiment of the designer crib sheet set of FIG. 1.

The broken lines shown in FIGS. 1 through 4 are indicative of back stitching.

The broken lines on the bottom of the sheet set in FIG. 3 are for environmental purposes only and form no part of the claimed design.

1 Claim, 4 Drawing Sheets
